ELECTROLYTIC CONDENSER

Joseph A. Poitras, Fort Lee, N. J., assignor to
 Solar Manufacturing Corporation, New York,
 N. Y., a corporation of New York

Application July 21, 1938, Serial No. 220,483

10 Claims. (Cl. 175—315)

This invention relates to electrolytic condensers, more particularly, to the anode terminal and the water-tight connection where the anode terminal passes through the container wall. This application is a continuation-in-part of my prior application Serial No. 55,330 filed Dec. 20, 1935. An object of the invention is to provide an anode terminal and water-tight sealing means where the terminal passes out of the container, which shall be of simple, inexpensive and durable construction, and one which will remain secure and water-tight for the life of the condenser. Allied to this object, is the devising of a method of making a satisfactory water-tight connection between the anode terminal and the container, which shall comprise the minimum of steps and which will quickly provide a tight connection at the lowest material and labor costs and one which will result in an anode terminal connection which will remain secure and tight for indefinite periods of time. A further object of this invention is to provide a terminal arrangement in which the means employed for holding the terminal in place and making a water-tight connection at the container, serves also as the electrical terminal connections.

For the attainment of these and such other objects as shall hereinafter appear or be pointed out, I have shown a number of embodiments of my invention in the accompanying drawing, wherein

Fig. 1 is a front view, partly in section, of an electrolytic condenser showing one form of my invention; Fig. 2 is a view of the lower portion of the condenser, also partly in section; Fig. 3 is a detail, in elevation, of the combined electrical connector and ring member; Fig. 4 is a plan view thereof; Fig. 5 shows in plan view another form of my invention; and Fig. 6, a sectional elevation, illustrates still another form of my invention.

The electrolytic condenser comprises a cylindrical container 10, the upper portion of which is contracted to form an inner bead or shoulder 11, for the purpose of seating a lid 12. The sheet of which the anode 30 is formed is a plate of thin aluminum foil of different width according to the predetermined capacity of the condenser and provided with several parallel rows of holes 31 to ensure an even and uniform circulation of gases and fluid through the condenser. The sheet is bent upon itself to form a plurality of folds or convolutions. The ends of the perforated and folded plate are brought to over-lapping relation and the lapped ends secured to

the vertical leg 22b of an L-shaped bracket 22, by means of rivets or other fastening means 22c. The horizontal leg 22a of the bracket is secured, as by screw or pin 23c, to the top end of terminal stud 23. Interposed between the anode plate 30 and the inside wall of container 10 is a perforated, non-conductive lining 20 of a suitable material, generally Celluloid, to keep the anode from contact with the container wall.

The lower end of container 10 is formed with a neck 10A, which is passed through the opening provided in the chassis frame 28; the outside of neck 10A is threaded for the nut 27 by means of which the container may be securely clamped to the chassis 28.

Through the neck 10A is passed the aforementioned terminal stud 23 and a medium soft rubber bushing 24. The upper end of stud 23 is provided with a flange or enlargement 23b which overlies the upper end of the rubber bushing. Against the lower end of the bushing is provided a "Bakelite" or fibre washer 25 which also underlies the lower end of container neck 10A. The bottom of the container is slightly tapered 10B; the rubber bushing is provided at its upper end with a bead 24b which seats in the said tapered bottom 10B of the container. The rubber bushing 24 is thus interposed between the flange 23b of terminal stud 23 and the washer 25. Hence by exerting pressure between the washer 25 and flange 23b of the stud, the soft rubber bushing may be squeezed and expanded to form a water-tight packing between the terminal stud and the container neck.

This squeezing pressure may be exerted on the rubber bushing by forcing the terminal stud downwardly (as viewed in Fig. 1) so that its flange 24b is made to approach the washer 25 and thus expand the rubber bushing 24 therebetween. I am aware that it has been in the past proposed to exert an expanding pressure upon a rubber packing or bushing to secure a water-tight connection at the container neck, by threading the protruding end of the terminal stud and screwing a nut or the like thereon and pulling the nut on tight. It has also been proposed to deform the protruding end of the stud, as by hammering it or flattening it to provide a head thereon which was supposed to prevent retractive movement of the stud and to result in a water-tight connection. But such constructions have proved unsatisfactory for a number of reasons, among which might be mentioned that the connection does not remain water-tight either by reason of the gradual loosening of the

nut, or because insufficient pressure had been originally exerted upon the rubber packing due to the difficulty in maintaining the packing under pressure while the protruding end of the stud is 5 being deformed and the difficulty in deforming the stud close to the bushing, in which case there immediately results a looseness which soon develops into a leaky condition, which is then further aggravated by reason of the corrosive 10 nature of the electrolyte. Also the provision of threads on the terminal stud causes a weakening thereof and is especially bad because of the corrosive electrolyte getting into, even in minute quantities, the threads.

15 By my invention, I am able to obviate all difficulties heretofore encountered, and to provide a connection which may be quickly and cheaply made and which at the same time will remain water-tight indefinitely. The protruding 20 end or shank 23a of the terminal stud is smooth and is encircled by a ring member 26. Member 26 is provided with a sleeve 26a, the bore of which is slightly greater than the diameter of the stud so that member 26 may be slipped thereon. The 25 sleeve is provided with one or more crimped points (preferably two, as shown) designated 26c. The method of forming the water-tight connection involves the pulling of the terminal stud 23 downwardly (as viewed in Fig. 1), the 30 stud being sufficiently long to extend beyond the sleeve of the member 26 to provide an end which may be conveniently grasped. The member 26 is meanwhile held firmly against washer 25; the downward pull on the stud causes a squeezing 35 or expansion of the rubber bushing 24, as already explained. When the stud is in a position exerting sufficient compression upon the rubber bushing, the ring member is secured to the stud—maintaining the bushing under compression—by 40 pinching in the two crimpings 26c to grip the stud. Thereafter the length of the stud extending beyond the sleeve of the ring member may be cut off.

The terminal stud is provided with a double 45 taper, clearly shown in Fig. 1, the upper portion of the stud being downwardly tapered 23X to waist line 23w and the lower portion being upwardly tapered 23Y to the waist line. The lower taper 23Y is preferably of less degree than the upper taper 23X. The purpose of the lower taper 23Y is to provide an appropriate abutting surface against which the ring member, after having been crimped or pinched together at 26c, may jam or be clamped and held under the expansive 50 pressure exerted by the compressed rubber bushing 24. The upper taper 23X is provided to increase the outwardly-expansive squeezing of the rubber bushing to further ensure its efficiency as a water-tight packing.

55 The taper 23Y may be made elliptical or non-circular, see Fig. 4, so that in crimping the ring member 26 to the anode stud 23, the sleeve 26a thereof will become deformed to a non-circular shape, and would thus be prevented from turning 60 on the stud or spindle 23.

A further aspect of this invention is the combining of the electrical binding or soldering post of the anode terminal with the water-tight packing means. This I achieve by providing on the 65 said clamping ring member 26 a pair of arms 26b (or a single arm, if preferred) perforated and adapted to be used for soldering or bolting electrical connection. By thus connecting the solder terminal itself to the anode terminal stud, a far 70 superior electrical contact arrangement is made

than that used in previous designs, as the terminal itself becomes a solid unit, homogeneous with the anode stud. Moreover, there is eliminated a separate member or members for the electrical connection.

The lower taper of the terminal stud may be eliminated and the ring member secured to a purely cylindrical stud, as shown in Fig. 5. The ring member 26, which is circular—as shown in dot-and-dash lines—and of somewhat larger bore than the stud 23', is slipped over the stud. After the parts are forced together for a water-tight fit, as described with reference to Fig. 1, the ring member, which is made preferably of steel, is forced together between the pair of dies 40. Sufficient pressure is exerted between the dies to deform the ring member 26 to the shape shown in the solid lines in Fig. 5. The stud 23' being made of a soft material, preferably aluminum, and the ring member being made of a much harder substance, preferably steel, portions of the ring become embedded in the stud to hold the two permanently in place, as clearly shown in the figure.

Instead of the long rubber bushing 24 shown in Fig. 1—which would be used where the container is provided with a threaded neck which is held to the chassis by the provision of a cooperative nut as shown in Fig. 1—, a rubber washer 41, see Fig. 6, may be used. In the form of the invention shown in Fig. 6, the container 10' has no neck portion; the condenser may be fastened to the chassis (not shown) in any desired manner, such as by flange 42. Interposed between the flange 23b of the terminal stud 23" and the floor of the container is a rubber washer 41, through which the stud passes. The washer is provided with a short hub 41h which encircles the stud and which is interposed between the stud and the edge of the terminal hole in the floor of the container, to serve as an electrical insulation between the stud and condenser container. The "Bakelite" washer 25 is placed on the outside of the container and the ring member 26 slipped over the protruding portion of the stud, which, incidentally, is considerably shorter than the stud 23 used in the construction of Fig. 1. After the parts are forced together to form a water-tight seal as already described, the ring member is secured to the stud either in the manner of Fig. 1 or of Fig. 5. If desired, the condenser may be fastened to the chassis by interposing the latter between the "Bakelite" washer 25 and ring member 26, but this would require that the condenser be attached to the chassis before the condenser is sealed by the securement of the ring member to the terminal stud.

I claim:

1. In an electrolytic condenser of the type wherein the container is provided with an opening at one end, the combination of a rubber bushing 60 received in the said container opening and provided at its upper end with a bead, an anode spindle passing through the inner bore of the said bushing and provided at its upper end with a flange, means for applying pressure to the said spindle to cause its said flange end to abut against the said beaded end of the bushing to compress the same, and means for maintaining the bushing in compressed condition.

2. A combined terminal and clamping member 70 for an electrolytic condenser of the type which includes a container provided with an opening at one end through which the anode spindle projects and a resilient member passing through the said container opening and provided with a 75

- passage for the said spindle, said combined terminal and clamping member comprising a ring member encircling the said spindle and formed with a crimped portion to clamp the said ring at a point on the spindle compressing the said resilient member to form a water-tight connection, the lower portion of the anode spindle being upwardly tapered to provide an abutting seat for the said ring.
10. 3. A combined terminal and clamping member for an electrolytic condenser of the type which includes a container provided with an opening at one end through which the anode spindle projects and a resilient member passing through the said container opening and provided with a passage for the said spindle, said combined terminal and clamping member comprising a ring member encircling the said spindle and formed with a crimped portion to clamp the said ring at a point on the spindle compressing the said resilient member to form a water-tight connection, the lower portion of the anode spindle being upwardly tapered to provide an abutting seat for the said ring, and the said tapered portion of the anode spindle being non-circular whereby the clamped ring is prevented from turning on the spindle.
4. A combined terminal and clamping member for an electrolytic condenser of the type which includes a container provided with an opening at one end through which the anode spindle projects and a resilient member passing through the said container opening and provided with a passage for the said spindle, said combined terminal and clamping member comprising a ring member encircling the said spindle, the lower portion of the said spindle being provided with an upwardly directed taper cooperative with the said ring member to maintain the said resilient member in compressed condition exerting a downward pressure against the ring member.
5. A combined terminal and clamping member for an electrolytic condenser of the type which includes a container provided with an opening at one end through which the anode spindle projects and a resilient member passing through the said container opening and provided with a passage for the said spindle, said combined terminal and clamping member comprising a ring member encircling the said spindle, the lower portion of the said spindle being provided with an upwardly directed taper against which the said ring member seats, and the upper portion of the spindle being provided with a downwardly directed taper whereby the said compressed resilient member exerts an outward expansive pressure to form a water-tight connection.
6. A combined terminal and clamping member for an electrolytic condenser of the type which includes a container provided with an opening at one end through which the anode spindle projects and a resilient member passing through the said container opening and provided with a passage for the said spindle, said combined terminal and clamping member comprising a ring member encircling the said spindle, the lower portion of the said spindle being provided with an upwardly directed taper cooperative with the said ring member to maintain the said resilient member in compressed condition exerting a downward pressure against the ring member, an integral

portion of the said ring member being formed as an electrical terminal post.

7. In an electrolytic condenser of the type wherein the container is provided with an opening at its bottom end, the combination of a rubber bushing received in the said container opening and provided at its upper end with a bead, the portion of the bottom of the container bordering its said opening being tapered to underly the said beaded end of the rubber bushing, an anode spindle passing through the inner bore of the said bushing and provided at its upper end with a flange, means for applying pressure to the said spindle to cause its said flange end to abut against the said beaded end of the bushing to compress the same, and to seat the beaded end of the bushing in the said tapered portion of the container bottom.

8. A combined terminal and clamping member for an electrolytic condenser of the type which includes a container provided with an opening at its bottom through which the anode spindle projects and a resilient member passing through the said container opening and provided with a passage for the said spindle, said combined terminal and clamping member comprising a ring member encircling the said spindle, the said anode spindle being headed and the said resilient member being interposed between the head of the spindle and the container bottom, the said ring member being adapted to clamp the spindle at a point compressing the said resilient member to form a water-tight seal.

9. A combined terminal and clamping member for an electrolytic condenser of the type which includes a container provided with an opening at its bottom through which the anode spindle projects and a resilient member passing through the said container opening and provided with a passage for the said spindle, said combined terminal and clamping member comprising a ring member encircling the said spindle, the said anode spindle being headed and the said resilient member being interposed between the head of the spindle and the container bottom, the said ring member being adapted to clamp the spindle at a point compressing the said resilient member to form a water-tight seal, an integral portion of the said ring member being formed as an electrical terminal post.

10. A combined terminal and clamping member for an electrolytic condenser of the type which includes a container provided with an opening at its bottom through which the anode spindle projects and a resilient member passing through the said container opening and provided with a passage for the said spindle, said combined terminal and clamping member comprising a ring member encircling the said spindle, the said anode spindle being headed and the said resilient member being interposed between the head of the spindle and the container bottom, the said ring member being adapted to clamp the spindle at a point compressing the said resilient member to form a water-tight seal, the said resilient member being provided with a hub portion interposed between the said anode spindle and the edge of the container bottom to afford an electrical insulation between the anode and the container.
